United States Patent

Des. 238,550
Patented Jan. 27, 1976

238,550

BEVERAGE CONTAINER OR THE LIKE

Bryant Edwards, Clarendon Hills, Ill., assignor to Illinois Tool Works Inc., Chicago, Ill.

Filed May 13, 1974, Ser. No. 469,209

Term of patent 14 years

Int. Cl. D9—01

U.S. Cl. D9—28

Fig. 1

Fig. 2

*Fig. 3*FIG. 1 is a perspective view of a beverage container or the like showing my new design;

FIG. 2 is a side elevational view, the opposite side being the same in appearance as the side shown; and
FIG. 3 is a top plan view on an enlarged scale.

I claim:

The ornamental design for a beverage container or the like, as shown and described.
